UNITED STATES PATENT OFFICE.

CHARLES A. MINER, OF KALAMAZOO, MICHIGAN, ASSIGNOR TO LIMOUSINE TOP CO., OF KALAMAZOO, MICHIGAN.

VEHICLE-BODY.

1,307,787.

Specification of Letters Patent. Patented June 24, 1919.

Application filed October 5, 1917. Serial No. 194,854.

To all whom it may concern:

Be it known that I, CHARLES A. MINER, a citizen of the United States, residing at the city and county of Kalamazoo, State of Michigan, have invented certain new and useful Improvements in Vehicle-Bodies, of which the following is a specification.

This invention relates to improvements in vehicle bodies.

10 The main objects of this invention are:

First, to provide an improved vehicle body having adjustable panels and removable uprights between the panels.

Second, to provide an improved vehicle

15 body having adjustable panels in which the panels may be quickly and easily adjusted to open or closed position and rigidly secured in either position.

Further objects, and objects relating to 20 structural details, will definitely appear from the detailed description to follow.

I accomplish the objects of my invention by the devices and means described in the following specification. The invention is 25 clearly defined and pointed out in the claims.

A structure which is a preferred embodiment of my invention is clearly illustrated in the accompanying drawing, forming a part of this specification in which:

30 Figure I is a side view of a structure embodying the features of my invention, the front part of the vehicle body being broken away.

Fig. II is a similar side view with the 35 panels lowered and the panel uprights removed.

Fig. III is an enlarged detail section on a line corresponding to the broken line 3—3 of Fig. I, with the panel raised.

40 Fig. IV is a similar detail section with the panel lowered.

Fig. V is an enlarged detail section on a line corresponding to line 5—5 of Fig. I with the panel lowered.

45 Fig. VI is a detail side elevation of one of the panels.

Fig. VII is an enlarged detail section on a line corresponding to line 7—7 of Fig. I, showing details of one of the uprights.

50 Fig. VIII is a detail section on a line corresponding to line 8—8 of Fig. VII.

Fig. IX is a detail plan view of one of the female coupling members.

55 Fig. X is a perspective view of a coacting pair of coupling members shown in locked

position by dotted lines and in partially disengaged relation by full lines.

In the drawing similar reference characters refer to similar parts throughout the several views, and the sectional views are 60 taken looking in the direction of the little arrows at the ends of the section lines.

Referring to the drawing, 1 represents the vehicle body proper, 2 the top or "deck." The top is supported at its front end by the 65 permanent uprights or posts 3 and at its rear end by the permanent wall 4. The structure illustrated has adjustable side panels 5, 6 and 7, separated by the removable posts or uprights 8 and 9.

The doors 10 and 11 and the body portion 12 are provided with chambers 13 adapted to receive the panels 5, 6, and 7, respectively. The panels are glazed panels comprising 75 frames or sashes in which the glass is set. The joints of the panels are not shown in the accompanying drawings.

At the outer edge of the openings to the chambers 13 I mount panel retaining strips 14. These strips project like flanges and 80 are adapted to engage the grooves 15 in the lower edges of the panels. The top is rabbed at 16 to receive the upper ends of the panels.

Clamping screws 17 are arranged through 85 sleeves 18 set into the inner sides of the body members. The panels are provided with extensions 19 at their lower ends upon which the screws may be clamped when the panels are in their elevated or raised position, as shown in Fig. III. When in their lowered or closed position, the screws engage the top members of the panel frames, as shown in Fig. IV. Other clamping means might be utilized, but the set screws are 90 simple and practical.

With this arrangement the panels may be 95 quickly released and lowered into the chambers provided therefor or raised and secured by swinging their lower ends out and engaging the same with the strips 14 and tightening the clamping screws 17.

The uprights 8 and 9 are secured by coacting male and female coupling members 100 20 and 21, respectively. The male coupling members are set into recesses 22 formed in the ends of the uprights so that their attaching flanges 23 are flush with the ends of the uprights and their engaging tongues 24 project therefrom. The female coupling mem- 110

bers 21 are set into recesses formed in the body and top, so that their surfaces are flush, as best shown in Fig. VIII. The engaging parts of the coupling members are 5 tapered inwardly so that a wedging action is secured.

10 Spindles 25 are arranged longitudinally through the male coupling members and provided with finger pieces 26 at their outer ends and latches 27 at their inner ends. The female coupling members are notched at 28 to receive the latches when they are turned to engaging position.

15 Stops 29 are adapted to swing against the top of the female coupling members to stop the latches in their disengaged position. The female coupling members are secured by screws 30 arranged through holes 31 in the bottoms of the dovetailed grooves thereof. 20 The male coupling member is secured by screws 32 arranged through holes 33 and flanges provided on the male coupling member,—see Fig. VIII.

25 With the parts thus arranged, they may be very quickly and easily assembled and disassembled and when assembled are very secure and rigid and are tightly secured so that there is no rattling between the parts.

30 I have illustrated and described my improvements in one form in which I have embodied the same. I have not attempted to illustrate or describe other forms or embodiments contemplated by me, as I believe the disclosure made will enable those skilled in 35 the art to which my invention relates to embody or adapt the same as may be desired.

Having thus described my invention, what I claim as new and desire to secure by Letters Patent, is:

40 1. In a structure of the class described, the combination of a body and top, a removable upright, dovetailed male coupling members set into recesses in the ends of said upright, their body portion being flush with 45 the ends of the upright and with their engaging portion projecting, coacting dovetailed sockets set in recesses in said body and top flush with the surfaces thereof, the dovetailed engaging parts of said coupling members being inwardly tapered, and spindles 50

disposed longitudinally through said male coupling members and provided with latches at their inner ends adapted when in one position to engage the inner ends of the female coupling members. 55

2. In a structure of the class described, the combination of a body member, a removable member, coacting dovetailed male and female coupling members mounted on said removable and body members, the dovetailed engaging parts of said coupling members being tapered, and a spindle disposed longitudinally through the male coupling member and provided with a finger piece at its outer end and a latch at its inner end, the 60 inner end of the female coupling member being recessed to receive said latch when in engaging position, said latch being provided with a positioning stop adapted to engage the top of said socket member when the 65 latch is in its disengaged position.

3. In a structure of the class described, the combination of a body member, a removable member, coacting dovetailed male and female coupling members mounted on said 70 removable and body members, and a spindle disposed longitudinally through the male coupling member and provided with a finger piece at its outer end and a latch at its inner end, the inner end of the female 75 coupling member being recessed to receive said latch when in engaging position, said latch being provided with a positioning stop adapted to engage the top of said socket member when the latch is in its disengaged position. 80

4. In a structure of the class described, the combination of a body member, a removable member, coacting dovetailed male and female coupling members mounted on said 85 removable and body members, and a spindle disposed longitudinally through one coupling member and provided with a latch adapted when in one position to engage the other coupling member. 90

95 In witness whereof, I have hereunto set my hand and seal in the presence of two witnesses.

CHARLES A. MINER. [L. s.]
